UNITED STATES PATENT OFFICE.

HENRY BARTH, OF CINCINNATI, OHIO, ASSIGNOR TO AMERICAN TYPE FOUNDERS COMPANY, OF NEW YORK, N. Y., A CORPORATION OF NEW JERSEY.

DESIGN FOR A FONT OF BORDER-TYPE.

SPECIFICATION forming part of Design No. 35,966, dated June 24, 1902.

Application filed May 26, 1902. Serial No. 109,119. Term of patent 14 years.

To all whom it may concern:

Be it known that I, HENRY BARTH, of Cincinnati, in the county of Hamilton and State of Ohio, have invented and produced a new and original Design for a Font of Border-Type, of which the following is a specification.

This font comprises eighteen characters, five of said characters being the reversal of five others, and six of said characters being especially designed as corner-pieces. Of these the two at the extreme ends of the top line consist of scrollwork more or less grotesque and bulgy in character. The two middle characters in said line, one being the reversal of the other, have for their characteristic a conventional flower with a grotesque stemwork somewhat similar to the corner characters first referred to. Between the first and second characters in the top line is a heavy V-shaped character composed of curved lines, and between the third and fourth characters in said line is a small corner-piece quite thick at its angle and slightly curved at each end, its ends pointing at right angles. The characters in the second line are of irregular dash form, one of them being bow-shaped, and all of them being irregular in outline. The third line has at each end a

corner-piece, that at the right being of somewhat-exaggerated S shape, that at the left being a reversal of it, the second character from the left being also S-shaped, but greatly elongated and very grotesque, the middle portion and the curves being very thick and heavy. Next to this character are two characters, the one a reversal of the other, somewhat pear-shaped, with their smaller ends pointing in opposite directions, and next to them are two characters, also reversals, the right-hand of which is S-shaped, but simpler than the other S-shaped characters of the font, being very heavy at its middle, its extremities being short. The remaining character is of double V shape, resembling somewhat a pair of ram's horns.

All of the characters comprising this font are solid and heavy.

What I claim as my invention is—
The design for a font of border-type as herein shown and described.

In testimony whereof I hereunto set my name this 14th day of May, 1902.

HENRY BARTH.
